TELEVISION TRANSMISSION

Fritz Schröter, Berlin, Germany, assignor to Tele-funken Gesellschaft für Drahtlose Telegraphie m. b. H., Berlin, Germany, a corporation of Germany

Application June 14, 1934, Serial No. 730,593
In Germany July 29, 1933

6 Claims. (Cl. 178—7.2)

The invention relates to the synchronous electrical distance transmission of the picture and tone portion of normal talking films.

- It has for its purpose, despite the necessary retaining of the film velocity established by the sound record reproduction, which today by established practice is normally 24 frame widths per second, which may be illustrated by way of example, to make possible a higher number of pictures for the optical part of the transmission. It has been found that in the recently attained brilliancies of the picture screen, in particular by the use of the Braun or cathode ray tube (the "kinescope") as a television picture producer, that the alternation of 24 pictures per second frequently ceases to act sufficiently free of flickering, and that a quiet facial impression can only be attained at a somewhat higher alternation frequency.
- 20 In accordance therewith the present invention resides in the use and combination of methods and arrangements which in the normal, for the tone recording properly adjusted advance of the film, permits of the scanning of a great many 25 more pictures at the same time than picture frames of normal dimension are mechanically released. In the following it is assumed, for purposes of example and illustration only, that the required number of optical transmissions per 30 second, herein designated by n , is equal to 36. The invention, however, permits of any other value for n and any desired proportion of this n to the acoustically established value, designated as n' , which today = 24.
- 35 Fig. 1 shows the relative position of the scanning beams and frames of a continuously moving film at different time intervals.

Fig. 2 shows diagrammatically an apparatus for performing the invention.

- 40 For the solution of the present problem an optical picture compensation method is inserted for the television scanning, and which at keeping constant $n' = \text{normal} = 24$, permits an independent n, n' for the frequency of the light electrical 45 decomposition and recombination of the picture mosaic. An embodiment of the invention comprises making a special photographic copy from the talking film to be transmitted, having in the length of $n' = 24$ normal widths of pictures a 50 greater number of pictures correspondingly smaller in accordance with the assumption $n = 36$. The reduction can be limited to the coordinate parallel to the advance of the film. This transformation of the respective section of the 55 cinematographic act from 24 to 36 individual

phases or frames can be accomplished in various ways. One way resides in interconnecting an optical picture balancer between the original standard film and the copy to be made therefrom. In reproducing in this way the uniformly advanced original negative, or a positive made therefrom, by means of a Mechau projector (as illustrated, for example, by U. S. Patent 1,584,817 granted to E. Mechau on May 11, 1926) or an equivalent device with proper reduction, on the 10 step-like advanced copying strip, for example by means of a Maltese cross, and in selecting 36 steps for 24 standard picture frames of film length advanced, due to the continuous excess shutting of the individual picture phases there 15 will be obtained on the copy the desired increased number of discrete, sharp pictures of reduced size, and hence a film is obtained directly suited for the standard television scanning and which may have the sound record copied at the edge 20 thereof.

In another way the photographic transmission can be carried out on an auxiliary strip at a rational proportion n/n' for instance also 36/24, by means of special copying machines. These 25 devices operate by the use of rhythmically controlled, and operated shutters in such manner that at a corresponding reduction of the size of the picture at least of the width of the picture in the proportion 36/24, for each 2 picture frames 30 or phases of the original, three picture frames or phases of the copy are produced, in that, for instance, each 1, 3, 5, etc., individual picture of the original is twice copied in succession, while each 2nd, 4th, 6th, etc., will be copied only once. 35 Hence for 24 advanced frame widths of the original (12 times 2 plus 12 times 1) 36 reduced pictures are obtained in the copy. It is obvious that already at the original production of the respective talking film, besides the ordinary apparatus 40 a second apparatus can be synchronously operated therewith which as aforementioned receives for a length of n' standard widths of the picture, directly n, n' pictures.

Besides the photographic compensation on the 45 film band proper the invention can also be put into practice in such manner that the picture series of the standard talking film band is projected on the scanning field of the television decomposer in an optical way by means of a continuous compensation arrangement operating 50 with excess shutting of the picture phases, i. e., again across a Mechau projector. The film hereby passing at standard speed ($n' = 24$) through the Mechau projector and the sound receiver, be in 55

the special case, projected on a Nipkow disk having spiral circles of holes, and which operates in the known manner. Hence due to the superposition of the individual pictures on the disk without 5 interruption or gaps, a forced ratio of reduction between the disk and the transport movement of the film is not required; the Nipkow disk on the contrary may be driven, entirely independent, with that number of revolutions corresponding 10 to the desired increased n of the optical scanning.

A third possibility for carrying out the invention is obtained by the use of the so-called Braun or cathode ray tube as picture scanner. This 15 application has been proposed already in various instances. It consists in moving the point of light on the fluorescent screen of the tube in the sense of the decomposition of the picture whereby it can be sharply projected through a lens on to the 20 film to be transmitted. A photoelectric cell disposed in back thereof receives in accordance with the distribution of the black portions in the picture of the film a greater or smaller amount of light. Since a continuous advance of the picture 25 band automatically furnishes the cross component of the television decomposition in this arrangement the point of light can be limited to its movement within always the same trace of lines. This type of scanning, as is known, can be accomplished 30 in the cathode ray tube by means of relaxation oscillation deviating the electron beam at constant velocity along the picture line in order to cause it to suddenly return to the starting point at the end of the line.

35 In order to carry out the invention by means of such cathode ray scanner, in addition to the before described operating performance, an electrically or magnetically effected periodical lateral displacement of the course of the picture points 40 is carried out at right angle to the line. This displacement is transmitted to the picture film by means of the projector lens. The resultant rhythmic movement of the cross line is against the movement of the film operating at standard 45 speed, until under the influence of the second relaxation oscillation by which it is controlled, it suddenly jumps back into the starting point. Then it begins anew.

This type of performance is schematically 50 shown in Figure 1 of the drawing wherein there is indicated eight different phases I—VIII of the displacement of the film band shown in cross section, whose individual lengths of the pictures is shown by the section 1, 2, 3, etc. The film moves 55 in a continuous fashion and not in sudden steps, in the direction of the arrows 3. Against this film there moves the location of the scanning line in the sense of arrow 10; however the same jumps back over an entire width of the picture within 60 regular time intervals corresponding with the phases II, V, VIII (arrow 9). While the film in the example chosen ($n=36$, $n'=24$) advances at $\frac{2}{3}$ of its standard width of the picture, the scanning movement of the cross line of the point of 65 light moves towards the film at $\frac{1}{3}$ of the width of the picture. After an advance of the film of 2 times $\frac{2}{3}=2$ normal picture widths, the course of the point of light hence has continuously passed over and scanned in lines 3 full pictures, 70 as seen from Figure 1. If therefore the band of the talking film is moved at a standard speed $n'=24$ picture widths per second, the light point decomposes in this line 24 times $\frac{2}{3}=36$ pictures. The dotted line represents the displacement as 75 to time of the scanning line, and hence also the

shape of the voltage of the relaxation oscillation necessary for the cathode ray deviation. In the intervals 1—1', 1'—1'', 1''—1''' the snapping back of the cathode ray, i. e., the relaxation of the voltage at the important pair of deviation plates, takes place.

An example of one suitable arrangement for carrying out this control is shown in Figure 2. The film 1 is continuously moved and thereon the line 2 of the light point of the cathode ray tube of which only the end surfaces of the bulb 13 is indicated, is correspondingly reduced and sharply reproduced by means of the lens 7. The incident light is passed to the photoelectric cell 9 by means of lens 8. The plate pair serving for the line deviation of the light point is not shown in the drawing. At 90° displaced thereto, there is provided a second plate pair 3, for the required cross displacement in the sense of the invention, of the scanning line 2 on the screen of tube 13, or on the film 1 respectively. This plate pair 3 is in parallel to the condenser 4, which can be periodically charged by a direct voltage source 5 across a resistance 6. The entire arrangement 20 conforms with an ordinary relaxation circuit, and hence all means known in such arrangements for obtaining a definitely shaped charging current curve, can be applied, for instance, in place of an ohmic resistance 6, an electron tube operating in the region of saturation, or better a pentode 30 can be used whose anode current remains constant within a wide interval of the plate potential. For the discharge of the condenser 4 or the plate pair 3 respectively, a controlled discharge tube 12 serves, for instance, a glow relay or "thyatron", 35 whose grid is positively charged by a periodically operated switch 11 which is controlled by the movement of the film. To this end the film is passed over rollers 10, with which the switching device 11 is coupled in a forced manner in the 40 proper ratio of reduction. In this manner the cross movement of the line of the cathode ray, shown in Figure 1, can be easily and simply controlled practically without energy, and thus the desired compensation of the picture can be obtained.

The relaxation oscillation required for the compensation of the pictures and produced according to the method in Figure 2, may be used at the same time for the synchronization of the 50 cross deviation of the electron beam in the picture receiver. Herby it is necessary to transform upwards the relaxation frequency in the proportion $\frac{1}{3}$, since according to Figure 1 there corresponds with the interval between the individual relaxation performances, the threefold transmission of the picture field. This frequency ratio is not required to be carried out in the receiver, it can be produced already in the transmitter by means known as such.

The invention is, of course, capable of modification and I, therefore, believe myself to be entitled to make and use any and all modifications thereof which fall fairly within the spirit and scope of the hereinafter appended claims.

What I claim and desire to protect by Letters Patent is:

1. In television apparatus, a motion picture film of which the electro-optical image reproduction of each film frame area is to be produced at a 70 distance point, means for moving the film at a pre-established constant speed past a point of analysis, a cathode ray tube having means there-in to produce a point source of light of elemental area, an optical system to direct the light 75

- produced within the cathode ray tube upon the film to illuminate an area of proportional size on the film, and a light translating device for producing when illuminated in accordance with the varying densities of the film record as illuminated by the cathode ray spot varying electrical energy output corresponding to the film density at the elemental area instantaneously illuminated, deflecting means associated with the cathode ray tube for causing the cathode ray beam developed to scan the film transversely in a line for line manner during the film motion past the predetermined point and a second deflecting means for causing the line for line scanning of the film frame areas passing before the predetermined point to be of a different number than the lines of elemental width of the film actually passing the said predetermined point within the said predetermined time period. 5
- 20 2. In television apparatus, a motion picture film record of which the electro-optical image reproduction of the successive film frame areas thereof is to be produced, means for continuously moving the film past a predetermined point at a pre-established constant rate corresponding to the rate of film motion suitable for the translation of the sound record accompanying the film frame areas into electrical signaling impulses, a cathode ray tube having means therein to develop a point source of light for illuminating an area of elemental size on the film record, a light translating device arranged to receive light corresponding to the varying densities of the film record as illuminated by the cathode ray light spot impinging thereon, means for causing the cathode ray light spot to traverse the film frame areas in a direction transverse to the direction of film motion at a predetermined rate so that each film frame area is illuminated with a series of substantially parallel paths of light of equal number, and means for causing the illuminated cathode ray spot to scan a different number of equal length transverse paths across the film than the number of such paths of elemental width which pass the predetermined point within a predetermined time period. 30
- 35 3. A system for scanning film for the television transmission of electro-optical reproductions of the independent film frame areas which comprises means for moving the film continuously past a predetermined point at a predetermined pre-established constant rate corresponding substantially to the rate at which the sound recordings on the film are to be translated into electrical signaling impulses, a cathode ray tube for producing a spot of light for illuminating the film along a series of paths each of elemental width transverse to the direction of motion of the film, and means for causing the cathode ray spot to be displaced in a second direction at right angles to that along which the film is illuminated so that a different number of film frames may be exposed to an identical number of transverse paths of light in a predetermined time period than the number of film frames which pass the predetermined point in the same time period. 40
- 45 4. The method of producing television images from a motion picture film record which includes the steps of moving the film record continuously at a pre-established constant rate past a predetermined plane of analysis, developing an electron beam within an electron tube and converting the produced beam into a point source of light of elemental size to illuminate an elemental area of proportional size on the film record, translating the light values on the illuminated elemental film areas into electrical energy of amplitude varying in accordance with the densities of the elemental areas of the film record illuminated, tracing the developed light spot across the film record in a path transverse to the film motion so as to scan the same along a path transverse to the path of film motion past the predetermined plane deflecting the produced electron beam simultaneously in a direction normal to the plane of the transverse light path traces and controlling the last named deflection in accordance with the film motion to return the beam at predetermined time periods to a plane of initial transverse deflection so that a different number of transverse light traces of the film are made during a predetermined time period than the actual number of transverse paths of the same width which pass the said predetermined plane of analysis with the fixed predetermined time period. 5
- 50 5. The method of producing television from a motion picture film record continuously which comprises moving the film record at a pre-established constant speed past a point of analysis, developing a cathode ray beam to produce a point source of light of elemental area on the film, producing electrical impulses of variable amplitude proportional to the varying shade densities on the elemental areas of the film record as illuminated by the cathode ray beam, continuously deflecting the cathode ray beam in a plane transverse to the film motion to scan the film transversely in a line for line manner during the film motion past the predetermined point, then deflecting the developed beam in a second direction normal to the plane of the first deflection simultaneously with the film motion, and controlling the cycle of the second named deflection in accordance with the film motion to return the beam to an initial plane of transverse deflection at predetermined time intervals for causing the line for line scanning of the film frame areas passing before the predetermined point to be of a different number than the lines of elemental width of the film actually passing the said predetermined point within the said predetermined time period. 35
- 55 6. In television apparatus, a motion picture film of which the electro-optical image reproduction of each film frame area is to be produced at a distance point, means for moving the film at a pre-established constant speed past a point of analysis, a cathode ray tube having means therein to produce a point source of light of elemental area, an optical system to direct the light produced within the cathode ray tube upon the film to illuminate an area of proportional size on the film, and a light translating device for producing when illuminated in accordance with the varying densities of the film record as illuminated by the cathode ray spot varying electrical energy output corresponding to the film density at the elemental area instantaneously illuminated, deflecting means associated with the cathode ray tube for causing the cathode ray beam developed to scan the film transversely in a line for line manner during the film motion past the predetermined point and a second deflecting means for causing the line for line scanning of the film frame areas passing before the predetermined point to be of a greater number than the lines of elemental width of the film actually passing the said predetermined point within the said predetermined time period. 60
